UNITED STATES PATENT OFFICE.

DANIEL M. GRAHAM, OF BOSTON, MASSACHUSETTS.

APPARATUS FOR VAPORIZING AND BURNING PETROLEUM.

SPECIFICATION forming part of Letters Patent No. 276,578, dated May 1, 1883.

Application filed September 30, 1882. (No model.)

To all whom it may concern:

Be it known that I, DANIEL M. GRAHAM, of Boston, in the county of Suffolk, of the State of Massachusetts, have invented a new and useful Improvement in Apparatus for Vaporizing or Burning Petroleum or other Hydrocarbon; and I do hereby declare the same to be described in the following specification, and represented in the accompanying drawings, of

which—

Figures 1 and 2 are vertical sections, taken on planes at right angles to each other, of an apparatus embodying my invention, the nature of which is duly set forth in the claims hereinafter presented.

In the said drawings, A denotes a retort or tubular vaporizing or heating coil, which at its upper end opens into an inverted three-way tubular coupling, B. From one arm of this coupling a jet-pipe, C, provided with an air hood or pipe, D, having lateral perforations *a* in it, descends directly over a disk or deflector, E, placed on a horizontal pipe, F, which, arranged as shown, communicates with the other arm of the coupling B by means of a vertical pipe, G. The pipe F opens at its inner end into a residuum-receiver, H, which is a vessel open at one side, or at its bottom, and having to the opening a closing screw-plug, b.

Within the pipe F is a clearer, I, which is a cylindrical rod whose diameter corresponds to that of the bore of the pipe. This rod carries at its inner end a blade or scraper, c, whose width equals the diameter of the bore of the pipe.

At the outer end of the pipe F there is a stuffing-box, x, for the clearer I to slide and turn in, such box being to prevent the escape of gas or vapor from the tube.

In advance of the deflector E there is a jet-hole, d, made in the upper part of the pipe F, while below the pipe, and under such jet-hole, is a cup, K, between which and the pipe is a jet-pipe, L, which stands at right angles with the pipe F, and has an opening of discharge arranged in it, as shown at e in Fig. 1.

Resting on the pipe F, concentrically with its discharge-hole d, is a short chimney, M, which is directly underneath a disk or deflector, N. The said disk or deflector N is fixed to a hori-

zontal pipe, O, which opens into the retort or coil A, at its lower end, as shown in Fig. 1. The pipe O is over and parallel to the jet-pipe L, both pipes at their outer ends being provided with long conical valve-seats, as shown at f and g in Fig. 1, to receive similar-shaped valves, h and i, whose stems k and l extend through stuffing-boxes m and n, and are provided with screws o, and hand-wheels p, arranged as represented, such screws screwing into the heads q of the stuffing-boxes, whose packings are to be of asbestos, or some other proper material capable of withstanding an intense heat. The pipes O and L, by three three-way couplings, r, and two short pipes, s, 65 are made to communicate with a horizontal pipe, P, provided with a stop-cock, Q, and leading from a reservoir of petroleum.

The apparatus above described is supposed to be mainly within a stove or chamber, one side or part of which is shown at S, all the portions to the right of the said part S being without the said stove or chamber.

In order to put the apparatus in operation, an attendant first opens the lower valve, i, or moves it off its seat, the upper valve being closed. This will allow petroleum from the reservoir to flow into and through and out of the pipe L and drop into the cup K. The liquid petroleum in the cup is next to be enflamed, the flame passing upward against and above the pipes L and F, and through the chimney M, up against the deflector N, the pipe O, and into the coil or retort A, against which it will be deflected by the disk N. In 80 doing this the flame will heat the coil. After such coil and the pipe O may have been sufficiently heated the valve h is to be opened to allow the petroleum to flow into the coil, by which it will be immediately vaporized and converted into gas, which will pass by the pipe G into the pipe F, and thence out of the jet-hole d, and will be enflamed, the flame rushing upward through the chimney, and, mingling with air drawn into and through it, will 85 impinge against the deflector N and be deflected upon the coil A. This having taken place, the valve i is to be closed. By sliding and revolving the clearer I and its blade c within the pipe F any tar or residuum forming 90

or settling within the said pipe may be forced therefrom into the residuum-chamber H, as occasion may require. By means of the jet-pipe C and its perforated hood D and the deflector E further heating of the pipe F and the gases, when therein, may be effected.

By such an apparatus a very great heat may be produced within the stove or casing S and utilized as occasion may require.

- 10 I am aware that a clearer has been used in a boiler-tube for clearing it of deposits and forcing them out of such tube, and therefore I make no claim to such, as I use a clearer with a tube provided with a lateral opening, and 15 such clearer is to keep such opening from being clogged by deposits made in the bore of the tube and in and around the opening.

What I claim as my invention is as follows, viz:

- 20 2c 1. The combination of the pipes O, L, and P, arranged, connected, and provided with valves, substantially as described, with the retort or coil A, and the cup K, chimney M, and deflector N, all being arranged and to operate substantially as set forth.
- 25 2. The combination of the jet-pipe F, its clearer I, residuum-chamber H, and the conduit G, with the chimney M, deflector N, conduit C, coil A, and the pipes O, L, and P, ar-

ranged, connected, and provided with valves, 30 substantially as set forth.

3. The combination of the jet-pipe C, its hood D, and the deflector E, with the pipe F, clearer I, residuum-chamber H, and conduit G, and with the chimney M, deflector N, coil 35 A, and the pipes O, L, and P, arranged, connected, and provided with valves, substantially as set forth.

4. The clearer I, and its blade c, in combination with the jet-tube F and residuum-chamber H, arranged and combined with the retort A, substantially as set forth.

5. The combination of the clearer I with the induction-tube F, provided with the educt or hole d, leading laterally out of it, as set forth, 45 such clearer being to remove deposits from the mouth of such hole.

6. The combination of the clearer I with the induction-tube F, provided with a stuffing-box at one end for reception of the clearer, and 50 having a discharging educt or hole, d, leading laterally out of it, (the said tube,) all being substantially as set forth.

DANIEL M. GRAHAM.
